UNITED STATES PATENT OFFICE.

THOMAS J. SHAUGHNESSY, OF MARSHALL, MISSOURI.

SCAFFOLD-SUPPORT.

SPECIFICATION forming part of Letters Patent No. 290,487, dated December 18, 1883.

Application filed October 4, 1883. (No model.)

To all whom it may concern:

Be it known that I, THOMAS J. SHAUGHNESSY, a citizen of the United States, residing at Marshall, in the county of Saline and State of Missouri, have invented certain new and useful Improvements in Scaffold-Supports; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements upon that class of adjustable scaffolds in use by plasterers, painters, and interior decorators, the object being to produce an apparatus which, while retaining its portable character, is readily adjusted to different heights, so that the user may be brought into the most desirable position in relation to the work upon which he is engaged.

The invention may be said to consist, essentially, in the constructions of a series of tripods, the legs of which are adjustable, so that they can be spread apart or brought nearer together, thus raising or lowering the apex of the tripod, which supports suitable bearers, upon which the scaffold-boards are laid, the whole being constructed and arranged as hereinafter described, with the points of the invention specifically stated in the claims.

In the accompanying drawings, in which similar letters indicate like parts in the several figures, Figure 1 is a perspective view of a pair of the tripods with the bearer or supporting-beam placed upon them. Fig. 2 is a side view of one of the tripods. Fig. 3 is an end view of the same, and Fig. 4 shows one of the tie-bars and the manner of its connection to the cross-bar of the tripod.

The tripods, which form the principal part of this invention, are each composed of two legs, A A, of equal length, united and held at a certain distance from each other by the cross-bar B, which is firmly secured by bolts or otherwise at either end to one of the legs A. The upper ends of these legs are bevelled and separated from each other suffi-

ciently to receive between them the movable leg C, which forms the third leg of the tripod, and swings freely upon a bolt, a, passing through all three legs at a point near the upper ends of the legs A. The leg C extends upward beyond this pivotal point, and is bifurcated, forming a seat for the reception of one end of the bearer D, the jaws of this bifurcation fitting snugly against the sides of the bearer and retaining it in its position without other fastening.

In order to retain the legs of the tripod in any desired position, and thereby control the height of the scaffold, a tie-bar, E, is employed, which is connected to the cross-bar B at one end by any suitable swivel-joint, and also to the leg C by means of a bolt, b, passing through the leg and through one of a series of holes formed in the bar E. It will be apparent that as the legs A A and C of the tripod are brought nearer together the bifurcated end of the leg C will be elevated, consequently causing the bearers D, and the scaffold supported by them, to occupy a higher or lower position, corresponding with the distance of the leg C of the tripod from the legs A A, the whole forming a reliable and easily-adjusted scaffold-support for the purposes named.

I am aware that adjustable scaffold-supports are not new, and that they have been formed as tripods, two of the legs of which, extending above the others, formed side supports to the bearers, the legs of said tripods being made longitudinally extensible in order to raise or lower the bearers, as in the patent to J. Gorham, June 13, 1882, No. 259,530, and I do not therefore claim this construction. My scaffold-supports differ from this, in the bearer being held between the bifurcated jaws at the upper end of one of the legs, and the raising and lowering of the apex of the tripod being accomplished by narrowing or spreading its base.

Having thus described my invention, I claim as new, and desire to cover by Letters Patent of the United States, the following:

1. As an improvement in scaffold-supports, the combination of the bifurcated leg C, legs A A, cross-bar B, and adjustable tie-bar E, all arranged for joint operation in the manner shown and described.

2. The combination, in a scaffold-support,

of tripods constructed and operating as described, each having a bifurcated leg, C, legs A, A, hinged to leg C at their upper ends, and connected near the bottom by cross-bar B and 5 extension-bar E, the whole carrying a bearer, D, to support the scaffold-boards, substantially as set forth.

In testimony whereof I affix my signature in presence of two witnesses.

THOMAS J. SHAUGHNESSY.
